UNITED STATES PATENT OFFICE.

OTTO JAEGER AND GEORGE SCHMIEDEL, OF NEW YORK, N. Y.

DESIGN FOR TEXTILE FABRIC.

SPECIFICATION forming part of Design No. 29,323, dated September 6, 1898.

Application filed May 25, 1898. Serial No. 681,742. Term of patent 3½ years.

To all whom it may concern:

Be it known that we, OTTO JAEGER and GEORGE SCHMIEDEL, residing at New York city, in the county and State of New York, have invented and produced a new and original Design for Textile Fabric; and we do hereby declare that the drawing accompanying this specification gives and conveys to any one skilled in the art of printing or weaving and manufacturing a clear understanding of the same, of which the following is a description, reference being had to the accompanying drawing, showing the same.

The essential features of the design for a textile fabric consist of a novel configuration

for such fabric, presenting artistic-shaped leaves and sprays connected by drooping pendants, &c., arranged around several groups, all as shown.

The design is intended to be repeated 20 throughout the length and breadth of a cut or web of fabric.

What we claim is—

The design for a textile fabric substantially as herein shown and described.

OTTO JAEGER.

GEO. SCHMIEDEL.
